UNITED STATES PATENT OFFICE.

CYRIL SAYERS, OF JERSEY CITY, NEW JERSEY.

LOOSE-LEAF BINDER.

1,153,713.

Specification of Letters Patent. Patented Sept. 14, 1915.

Application filed September 15, 1914. Serial No. 861,750.

To all whom it may concern:

Be it known that I, CYRIL SAYERS, a subject of the King of Great Britain, and a resident of Jersey City, in the county of Hudson and State of New Jersey, have invented a new and Improved Loose-Leaf Binder, of which the following is a specification.

My invention relates to binders—especially to that class of devices which are used to temporarily bind together a number of loose leaves, between suitable covers.

Its object is to provide an improved clamping device which will readily permit the covers to be separated sufficiently to allow leaves to be inserted or taken out without, at the same time, entirely disconnecting the covers.

A practical embodiment of my invention is shown in the accompanying drawings, to which reference is made in the following detailed description.

Figure 1 is a plan of the base or bottom portion of my device; Fig. 2 is a plan of a binder post; Fig. 3 is a plan of the clamping screw; Fig. 4 is a plan of the extensible, locking screw; Fig. 5 is a plan of the removable filler block; Figs. 1^a-5^a are corresponding side elevations of the parts shown in Figs. 1-5; Fig. 6 is an elevation, in section, on an enlarged scale, showing the position of all the parts when in use, and Fig. 7 is a similar view with the filler block removed and the upper cover raised.

The bottom or base comprises a nut 1 which is preferably recessed in the lower cover 2. Into this nut is screwed the male portion 3^a of the binder post 3. One or more of these posts being used, according to the number or thickness of the sheets 4 to be clamped or bound together—this being a common binder post extension construction.

A clamping screw 5 is inserted in the internally threaded portion 3^b of the binder post. This clamp screw has a bottom chamber 5^a and the head of said screw is internally threaded at 5^b, the two chambers being connected by a small hole which is shown in Figs. 6 and 7 filled by the stem 6^c. The head of the clamp screw has two opposite tangential side grooves 5^c which are cut deep enough to open up the bottom of the threaded chamber 5^b.

A locking screw 6, having a knurled, cuffed head 6^a, a conical portion 6^b, a stem 6^c, the lower end of which is enlarged into

a head 6^a, is contained in the chambers of the clamp screw. It may be screwed into the position shown in Fig. 6 or unscrewed and drawn upward as shown in Fig. 7, the head on the stem preventing it from being entirely withdrawn.

The upper cover 7 has secured to it or has recessed in it a plain washer 8 which lines up with a corresponding hole in the cover 65 and fits loosely over the binder post.

A filler block 9, which is preferably cup shaped has a countersunk portion or conical depression 9^a and has a slot 9^b extending in from one edge and the rim of the cup is cut away as shown at 9^c. It will readily be seen that this filler block will slip into the grooves of the head of the clamp screw 5 and that by inserting the lock screw 6 the conical portion 6^b will enter the conical depression of the filler block and hold it in place and that this has the same effect as lengthening the head of the screw 5.

From the foregoing construction it is evident that, by loosening the locking screw 80 and removing the filler block, the upper cover may be raised as shown in Fig. 7, giving ample room for the insertion or the taking out of the sheets 4, but that the cover is held by the stem of the locking 85 screw 6 and falls readily back to place. The filler block is then inserted and screwed down, or the locking screw may be put in first and its knurled surface used in screwing down the clamp screw. 90

What I claim is:

1. A binder post clamp screw having a body portion and a head portion, in combination with a removable filler block and means for securing said filler block to said 95 screw.

2. A binder post clamp screw having a head and a threaded body portion—said head being internally threaded, in combination with a removable filler block and a 100 locking screw—said locking screw being adapted to enter the internally threaded portion of said clamp screw to hold said filler block and said clamp screw together.

3. A binder post clamp screw having a 105 head and a threaded body portion—said body portion having an internal chamber and said head being internally threaded, a locking screw mounted in said clamp screw—said locking screw having a short threaded 110 portion and a long stem portion with retaining means at its lower end; in combina-

tion with a removable filler block which is adapted to be clamped and retained in position between said screws.

4. A clamp screw having a threaded body portion and a head—said head being internally threaded and having a pair of opposite tangential slots or grooves, in combination with a filler block which is adapted to enter said slots, and a locking screw which 10 is adapted to enter said clamp screw to lock said filler block and said clamp screw together.

5. In a loose leaf binder having two covers and a binder post extending between said 15 covers, a binder post clamp screw having a head and a threaded body portion, in combination with a removable filler block which is adapted to be inserted between the head of said clamp screw and one of said covers, 20 means for locking said filler block in place, said locking means having a limited withdrawal movement—whereby one of said covers may be withdrawn a limited distance

to permit the taking out or insertion of leaves without being entirely disconnected.

6. A binder post clamp screw having a head and a threaded body portion, in combination with a removable filler block and a locking screw mounted in the head of said clamp screw which is adapted to lock said 25 filler block and said clamp screw together—said filler block being of inverted cup-shape, having a slot cut in one edge thereof and having a central, conical depression—the head of said clamp screw being slotted to receive 30 said filler block—said locking screw having a cone shaped portion which is adapted to enter the conical depression in said filler block, substantially as shown and described.

In testimony whereof I affix my signature 35 in presence of two witnesses.

CYRIL SAYERS.
